UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,158,993.

Specification of Letters Patent.

Patented Nov. 2, 1915.

Application filed June 17, 1914. Serial No. 845,657.

To all whom it may concern:

Be it known that I, FRANK DUTCHER, a citizen of the United States, residing at Versailles, in the county of Allegheny and 5 State of Pennsylvania, have invented certain new and useful Improvements in Railway Signal-Torpedoes, of which the following is a specification, reference being had therein to the accompanying drawing.

10 This invention relates to improvements in railway signal torpedoes, and the primary object of my present improvement relates to the construction of a paper or fiber circular torpedo.

15 A further object of my present invention is to provide a circular torpedo having a paper or fiber case composed of three parts, the central or body portion having a depression for the explosive compound and a 20 surrounding laterally extending flange, the flange carrying at opposite sides circular flaps of a size corresponding to the extreme diameter of the body portion, so that the flaps when folded in and cemented efficiently 25 close the case with the explosive therein.

30 A further object of my invention is to provide a circular torpedo having a paper or fiber case with the body-portion carrying an annular laterally extending flange and one or more closing flaps of the same size 35 and shape as the body-portion, and a wad fitting in the depression over the explosive, the flaps cemented to the flange and the wad, thus efficiently inclosing the explosive 45 in the depression of the body-portion.

40 In the accompanying drawings—Figure 1 is a perspective view of my improved torpedo showing it in place on a railroad rail. Fig. 2 is a central sectional view of Fig. 1 taken at right angles to the rail attaching strap. Fig. 3 is a perspective view showing the case open and the explosive and wad in 45 separated relation, with a slight modification in the manner of attaching the rail-engaging strap.

45 In carrying out my present improvement, the torpedo case is composed of paper or fiber and comprises a body-portion 1, which has a bulged recess or cavity 2, to receive the explosive 3. This explosive 3 is made of a contour or shape corresponding to the internal contour of the recess 2, by making the tablet circular in form with one bulged side *a* and a flat side *b*. This body-portion 50 1 is provided with an annular laterally pro-

jecting flange 4, which surrounds the recess 2.

Attached to opposite points of the flange 4, are two circular flaps 5 and 6. These flaps are made integral with the body-portion, as shown at 7, thus forming an integral connection with the body-portion and these flaps are made of a size corresponding to the extreme diameter of the flange 4, so that when they are closed inward, one over 60 the other as shown, in Fig. 2, they completely cover the recess 2 and the flange 4.

Preferably, the recess 2 is coated with a suitable waterproof cement *c* and then the explosive tablet 3 placed therein. Cement *d* 70 is also placed between the explosive tablet 3 and a wad 9 of a size to fill the outer end of the recess 2, and to thereby inclose the explosive within the recess. The flap 6 is then folded inward on the tablet with a coating of cement *e* between the flap and the wad 9. In the construction shown in Figs. 1 and 2, the rail-engaging strap 10 is placed between the inner flap 6 and the wad 9. After these parts are in position, the outer flap 5 is then closed over this flap 6 with a suitable coating of waterproof cement *f* between the two flaps. In the form shown in 75 Fig. 3, the flap 5 is provided with one or more slits 11, through which the rail-engaging strap 10 may be threaded, thus attaching the strap to the outer flap 5, instead of having it placed between the inner flap 6 and the wad 9, as in Figs. 1 and 2.

80 It will be observed that the flaps 5 and 6 have only a relatively small hinged portion 7 connecting them with the periphery of the flange 4, whereby the flaps are held in position and made integral with the body-portion 1, so that they will be folded and cemented to make an efficient closure for the body of the torpedo case and the explosive. While I have shown and prefer to have the case provided with two flaps, as shown, yet I desire it understood that it would be within 85 the scope of the broad inventive idea to use, for instance, the single flap 6, and have it cemented in position, omitting the outer flap 5. In this event, the rail-engaging strap 10 would be between the flap 6 and the wad 9, as in Figs. 1 and 2.

90 Attention is directed to the construction whereby the annular flange 4 is provided. This flange performs a double function, one being to stiffen and maintain the form and 95 100 105 110

shape of the body-portion with its recess 2, and the other being to provide sufficient cementing surface between the flange and its adjacent flap 6, to firmly unite the flap with 5 the flange and body-portion to make a thoroughly waterproof joint and to maintain the torpedo in a stable and permanent form.

So far as I am aware, a torpedo wholly of paper or fiber, circular in form, has not 10 heretofore been made, with all of its consequent advantages which are recognized by those skilled in the art, as compared with torpedoes which have a rectangular periphery or form.

15 Having thus described my invention, what I claim and desire to secure by Letters Patent is—

1. An improved torpedo comprising a paper case, a tablet explosive therein, a 20 waterproof cement coating completely surrounding and inclosing the explosive and cementing it to the casing, and a closure for the casing, the closure being cemented to the tablet by the said waterproof coating.

25 2. An improved railway signal torpedo, comprising a non-waterproof paper casing, a tablet explosive therein, a waterproof cement coating completely surrounding and inclosing the explosive and cementing it to 30 the casing, and a closure for the casing, the closure being cemented to the tablet by the waterproof coating.

3. An improved railway signal torpedo comprising a non-waterproof paper casing, 35 a tablet explosive therein, a waterproof cement coating completely surrounding and inclosing the explosive and cementing it to the casing, a wad cemented to the bottom of the explosive tablet, and a closure for 40 the casing, the closure being cemented to the wad by the said waterproof coating.

4. An improved paper case torpedo comprising a casing, a tablet explosive within the said casing, a plurality of flaps carried 45 by the casing and adapted to close it, the

interior of the body-portion provided with a coating of waterproof cement completely surrounding the explosive tablet and holding it within the casing, the inner side of the flaps provided with a coating of cement, the flaps folded one upon the other, the flap adjacent the explosive tablet cemented to the wad whereby the explosive is held within a waterproof cement coating and whereby the parts composing the torpedo are cemented 55 together to form a composite article.

5. An improved railway torpedo comprising a non-waterproof paper casing, a tablet explosive therein, a waterproof cement coating completely surrounding and inclosing the explosive tablet and cementing it to the casing, an explosive holding and case stiffening wad cemented to the bottom of the explosive tablet, and a closure for the casing, the closure being cemented to the wad 65 by waterproof cement.

6. An improved paper case torpedo comprising a casing, a tablet explosive within the said casing, a plurality of flaps carried by the casing and adapted to close it, the 70 interior of the body portion provided with a coating of waterproof cement completely surrounding the explosive tablet and holding it within the casing, and an explosive holding and case stiffening wad cemented 75 to the tablet, the inner side of the flaps provided with a coating of cement and folded over one upon the other, the flap adjacent the wad cemented to the same, whereby the explosive is held within a waterproof cement coating, and whereby the parts composing the torpedo are cemented together to 80 form a composite article.

In testimony whereof I hereunto affix my signature in the presence of two witnesses. 85

FRANK DUTCHER.
